UNITED STATES PATENT OFFICE

2,566,891

TOGGLE-TYPE PICKER STICK LINKAGE

George H. Hufferd, Shaker Heights, Ohio, assignor to Houdaille-Hershey Corporation, Detroit, Mich., a corporation of Michigan

Application July 27, 1948, Serial No. 40,893

8 Claims. (Cl. 139—149)

1

This invention relates to a loom, and particularly to an improved linkage for controlling the movements of a picker stick of the loom.

As is well known, the proper control of the movements of the shuttle contacting portions of the picker stick is one of the most critical factors entering into the operation of a loom at high speed. It is essential that the shuttle contacting portion of the picker or similar element which is secured to the top of the picker stick traverses a substantially straight line path which is generally parallel to the path of movement of the shuttle along the lay of the loom. Any deviation from this path will adversely affect the operation of the loom and, under certain conditions, will cause the shuttle to be thrown out of the shed with the resultant shut down of the loom.

Linkages heretofore commonly employed in looms for controlling the movement of the picker stick embodied a cam-shaped member known as a picker foot which was secured to the lower portion of the picker stick and cooperated with a suitable fixed surface so that when a rocking movement was imparted to the picker stick by the conventional power lug, the picker stick would rock through a path which would cause the top end thereof to follow a substantially straight line path parallel to the path of movement of the shuttle. Such arrangement has not been entirely satisfactory inasmuch as the picker stick was not restrained against vertical upward movements and under high speed operation of the loom, the picker foot would be raised out of contact with its supporting surface and thus produce a substantial inaccuracy in the path of movement of the shuttle contacting portions of the picker stick.

Accordingly, it is an object of this invention to provide an improved linkage for controlling the movements of a picker stick of a loom wherein the position of the picker stick is positively controlled at all points throughout its normal stroke.

A particular object of this invention is to provide a control linkage for a picker stick of a loom wherein the picker stick is supported entirely from a bracket which is secured to the rock shaft of a loom, and the linkage interconnecting the picker stick with such bracket is so proportioned as to control the movement of the picker stick to move the shuttle contacting portions thereof along a substantially straight line path, generally parallel to the path of the shuttle along the lay.

Still another object of this invention is to provide an improved control linkage for a picker stick wherein a pair of toggle connected links are incorporated intermediate a bracket secured to

2

the picker stick and a bracket secured to the rock shaft of the loom.

The specific nature of this invention, as well as other objects and advantages thereof, will become apparent to those skilled in the art from the following detailed description of the annexed sheets of drawings which, by way of preferred example only, illustrate three specific embodiments of the invention.

On the drawings:

Figure 1 is a side elevational view of a control linkage for a picker stick embodying this invention showing the linkage in assembled relationship between a rock shaft of the loom and a picker stick.

Figure 2 is a slightly reduced scale top elevational view of the linkage of Fig. 1.

Figure 3 is an enlarged scale, side elevational view of a modified form of control linkage embodying this invention.

Figure 4 is a side elevational view of a picker stick control linkage embodying a still further modification of this invention.

Figure 5 is a schematic diagram illustrating the path of movement of the picker stick and the various components of the linkage embodied in the modification of Fig. 4.

As shown on the drawings:

Referring to Figure 1, the numeral 10 indicates the rock shaft of a conventional loom, while the numeral 11 indicates a conventional picker stick. The picker stick is supported for oscillating movements with respect to the rock shaft 10, hence with respect to the lay of the loom (not shown) by a linkage constructed in accordance with this invention which controls the movement of the picker stick so that the shuttle contacting portions of a picker (not shown), which is conventionally secured to the top end of the picker stick, traverses a substantially horizontal straight line path. In general, the linkage comprises a primary bracket 12, rigidly secured to the rock shaft 10, and a secondary bracket 13 which is rigidly secured to the lower portion of the picker stick 11 and connected to the primary bracket 12 by at least four links, respectively links 14, 15, 16 and 17, of which links 15 and 16 have one end thereof pivotally connected together in toggle arrangement.

In all modifications of this invention, at least one link, such as 14, is directly pivotally connected between the primary bracket 12 and the secondary bracket 13 and a pair of toggle connected links, such as 15 and 16, are also incorporated in the control linkage. However, the specific

connection of the toggle connected links varies in the different modifications.

Referring particularly to the modification of Figures 1 and 2, it will be seen that the primary bracket 12 constitutes an integral casting having at its lower portion a split extension 12a defining a suitable bore (not shown) for receiving the end of the rock shaft 10 therein. Primary bracket 12 is rigidly secured to the rock shaft 10 in any convenient manner, such as by a clamping bolt 18 which passes through integral depending wing portions 12b formed on the split extension 12a.

Immediately above the split extension 12a, the primary bracket 12 is provided with a boss 12c defining a pivot bearing 12d. In addition, the primary bracket 12 embodies an integral bifurcated extension 12e which projects upwardly and laterally with respect to the end of the rock shaft 10 and terminates in spaced boss portions 12f which define aligned pivot bearings 12g therethrough.

Secondary bracket 13 likewise constitutes an integral casting having a base portion 13a adapted to snugly engage against the front face of the lower portion of the picker stick 11 and to be rigidly clamped thereto by a bolt and nut unit 20 which passes through suitable apertures in the base portion 13a and in the picker stick 11. If desired, a clamping plate 21 may be provided adjacent the back face of the picker stick 11 which is also traversed by the bolt and nut unit 20.

Secondary bracket 13 is provided with integral, vertically spaced bosses 13b and 13c which respectively define pivot bearings 13d and 13e.

Considering now the arrangement of the various links 14 through 17, it is desired to point out that functionally, each of the links 14 through 17 may comprise either a single link, or a pair of spaced, parallel identical link elements, or a unitary forked link, depending entirely upon the nature of their pivotal supports. In the particular example shown in Figures 1 and 2 of the drawings, the link 14 is of double link construction. Link 15 is of single link construction, while the links 16 and 17 are of forked construction, having one end portion thereof bifurcated and the other end portion unitary.

The links 14 are each provided at opposite ends with pivot bearing bosses 14a and 14b respectively which permit such links to be pivotally mounted between the two lowermost pivot bearings of the primary and secondary brackets. A conventional form of pivot pin 22 may be employed to accomplish such mounting. In addition, the links 14 are each provided with a boss 14c which defines a pivot bearing 14d located intermediate the ends of each link 14. As previously indicated, the links 15 and 16 have their ends connected together in toggle fashion by pivot pin 23 and the other end of link 16 is then pivotally connected by pin 25 to the intermediate pivot bearing 14c provided by the link 14. The opposite end of link 15 is pivotally connected to the uppermost pivot bearing 12g of the primary bracket as by pivot pin 26.

Link 15 also is provided with an intermediate boss portion 15a defining an intermediate pivot bearing and the link 17 is connected by pins 24 between such intermediate pivot bearing 16c and the uppermost pivot bearing 13e defined by the secondary bracket 13.

With the described construction it is apparent that the movements of the picker stick 11 will be positively controlled throughout its entire

range. Furthermore, by proper proportioning of the various links, the movement of the picker stick 11 may be readily controlled so that the shuttle engaging portions of a picker (not shown) mounted on the top portion of the picker stick 11 will traverse a substantially straight line path. The dotted lines in Figure 1 illustrate an opposite extreme position of the picker stick 11 and the various components of the linkage. While the movements of the picker stick 11 are positively controlled by the described linkage, it will be noted that the required movements of the picker stick 11 may be freely accomplished without encountering any substantial frictional resistance from the controlling linkage.

In the modification of this invention illustrated in Figure 3 of the drawings, a primary bracket 30 and secondary bracket 31 are again respectively secured to the rock shaft 10 and the picker stick 11. However, in this modification, the primary bracket 30 is of somewhat different configuration from that of the modification heretofore described. In addition to a split cylindrical extension portion 30a which mounts on the rock shaft 10, the primary bracket 30 defines three pivot bearings 30b, 30c and 30d which are respectively located in vertically spaced relationship. Pivot bearing 30c is located intermediately of the other two pivot bearings and overlies the end portion of the rock shaft 10 and is defined by a webbed portion 30e of the primary bracket. The pivot bearings 30b and 30d are respectively located adjacent the top and bottom portions of an inclined bifurcated portion 30f of the primary bracket 30.

Secondary bracket 31 is of generally similar configuration to the modification heretofore described and is rigidly secured to the bottom portion of the picker stick 11 by bolts 32. Secondary bracket 31 defines a pair of vertically spaced pivot bearings 31b and 31c.

Again, four links 33 through 36 respectively are provided to connect the primary and secondary brackets and control the movements of the picker stick 11. The link 33 is pivotally connected between the uppermost pivot bearing 31c of the secondary bracket 31 and the intermediate pivot bearing 30c of the primary bracket 30 by pins 37. Links 34 and 35 have their ends pivotally connected by pin 37a to form a toggle and the free ends thereof are respectively connected to the uppermost pivot bearing 30d of the primary bracket 30 and the lowermost pivot bearing 31b of the secondary bracket 31 by pins 37b. The lowermost link 35 of the toggle connected link is provided, in addition, with an intermediate pivot bearing 35a, and the fourth link 36 is pivotally connected between such intermediate pivot bearing 35a and the lowermost link 30b provided on the primary bracket 30 by pins 37c.

It is therefore apparent that this modification also embodies a toggle controlled linkage, and by suitable proportioning of the dimensions of the links 33 through 36, the movements of the picker stick 11 may be controlled so that the shuttle contacting portions thereof traverse a substantially straight line path. Again the dotted lines indicate an opposite extreme position of the picker stick linkage range.

Referring now to Figures 4 and 5, a still further modification of this invention is illustrated. Again, a primary bracket 40 is provided which is secured to rock shaft 10 and a secondary bracket 41 is secured to the lower portion of the picker stick 11 by a bolt and nut units 42. Primary bracket 40 is of substantially identical configura-

tion to the primary bracket 12 described in detail in connection with Figure 1 and defines a pair of vertically spaced pivot bearings 40a and 40b. Likewise, the secondary bracket 41 is of substantially similar configuration to the secondary bracket 13 of the modification of Figure 1 and defines vertically spaced pivot bearings 41a and 41b which, however, are more widely separated than the corresponding pivot bearings in the modification of Figure 1.

Four links 43 through 46 are provided to connect the secondary bracket 41 to the primary bracket 40 and control the oscillating movements of the picker stick 11. Again, one of the links is directly pivotally connected between the primary bracket 40 and the secondary bracket 41. The link 43 is thus shown as having its end portions pivotally connected between the two lowermost pivot bearings 40a and 41a respectively of the primary and secondary brackets as by pins 47. The link 43 also defines an intermediate pivot bearing 43a. Links 44 and 45 have their ends connected in toggle fashion by a pivot pin 47a. The lowermost one of the toggle connected links, namely link 44, has its free end pivotally connected to the intermediate pivot bearing 43a provided on link 43 by pin 47b. The uppermost link 45 of the toggle connected links is provided with an intermediate pivot bearing boss 45a by which it is pivotally secured to the uppermost pivot bearing 40b of the primary bracket 40 by pin 47c. The free end of the uppermost toggle link 45 is then pivotally connected by pin 47d to one end of the fourth link 46 which has its other end pivotally connected by pin 47e to the uppermost pivot bearing 41b of the secondary bracket 41.

To more clearly illustrate the manner in which the toggle type linkages heretofore described effect the control of the movements of the picker stick, reference should be had to the schematic diagram of Figure 5. In this diagram, the picker stick, primary and secondary brackets, and the cooperating links are represented by line diagrams. The solid line drawings of these elements indicate the position of the various components of the linkage at the neutral or intermediate position of the picker stick 11. The dotted lines indicate the position of the elements of the linkage at the extreme inward position of the picker stick 11, while the dot-dash lines indicate the positions of the various components at the extreme outward position of the picker stick 11. In this schematic diagram, the picker element is represented by the short line 50 at the top of the picker stick 11 and it will be noted that the front face of this element traverses a substantially straight line path indicated by the line 51.

It is therefore apparent that this invention provides a greatly improved control linkage for controlling the movements of the picker stick of the loom to insure that the shuttle contacting portions of the picker stick will always traverse a substantially straight line path, even under high speed operation of the loom.

It will, of course, be understood that various details of construction may be modified through a wide range without departing from the principles of this invention and it is, therefore, not the purpose to limit the patent granted hereon otherwise than necessitated by the scope of the appended claims.

I claim as my invention:

1. A linkage for controlling the movements of a picker stick of a loom, comprising a primary

bracket adapted for securement to the rock shaft of the loom, a secondary bracket adapted for securement to a picker stick, means on each of said brackets defining a pair of vertically spaced pivot bearings, a first link pivotally connected between the two lower pivot bearings of said primary and secondary brackets, means on said first link defining a pivot bearing intermediate its ends, a pair of toggle connected links having the free ends thereof respectively pivotally connected between said intermediate pivot bearing on said first link and the upper pivot bearing on said primary bracket, one of said toggle connected links having a pivot bearing intermediately located thereon, and a fourth link pivotally connected between said intermediate pivot bearing on said toggle connected link and said upper pivot bearing on said secondary bracket, said links being proportioned to control the movements of said picker stick to shift the shuttle contacting portion thereof along a substantially straight line path.

2. A linkage for controlling the movements of a picker stick of a loom, comprising a primary bracket adapted for securement to the rock shaft of the loom, a secondary bracket adapted for securement to the lower portion of a picker stick, means on each of said brackets defining a pair of vertically spaced pivot bearings, a first link having pivot bearings thereon adjacent each end and an intermediate pivot bearing, said first link being pivotally connected between the two lower pivot bearings of said primary and secondary brackets, a second link having pivot bearings thereon adjacent each end and an intermediate pivot bearing, a third link having pivot bearings adjacent the end portions thereof, means connecting said second and third links in toggle relationship, means respectively connecting the free ends of said second and third links to said intermediate pivot bearing on said first link and the upper pivot bearing on said primary bracket, and a fourth link having pivot bearings adjacent the ends thereof, and means for pivotally connecting said fourth link between said intermediate pivot bearing of said second link and said upper pivot bearing on said secondary bracket, said links being proportioned to control the movement of said picker stick to shift the shuttle contacting portion thereof along a substantially straight line path.

3. A linkage for controlling the movements of a picker stick of a loom, comprising a primary bracket adapted for securement to the rock shaft of the loom, a secondary bracket adapted for securement to a picker stick, means on each of said brackets defining a pair of vertically spaced pivot bearings, a first link pivotally connected between the two lower pivot bearings of said primary and secondary brackets, a pair of toggle connected links, means for pivotally connecting the free end of said toggle connected links to an intermediate point on said first link, a fourth link pivotally interconnecting said other free end of said toggle connected links and said upper pivot bearing on said secondary bracket, and means pivotally connecting an intermediate portion of one of said toggle connected links with said upper pivot bearing of said primary bracket, said links being proportioned to control the movements of the picker stick to shift the shuttle contacting portions thereof along a substantially straight line path.

4. A linkage for controlling the movements of a picker stick of a loom, comprising a primary

bracket adapted for securement to a picker stick, means on each of said brackets defining a pair of vertically spaced pivot bearings, a first link pivotally connected between the two lower pivot bearings of said primary and secondary brackets, a pair of toggle connected links, means for pivotally connecting one free end of said toggle connected links to an intermediate point on said first link, a fourth link, means for pivotally connecting one end of said fourth link to the other free end of said toggle connected links and said other end of said fourth link to said upper pivot bearing on said secondary bracket, and means pivotally connecting an intermediate portion of the uppermost one of said toggle connected links with said upper pivot bearing of said primary bracket, said links being proportioned to control the movements of the picker stick to shift the shuttle contacting portions thereof along a substantially straight line path.

5. A linkage for controlling the movements of a picker stick of a loom, comprising a primary bracket adapted for securement to the rock shaft of the loom, a secondary bracket adapted for securement to a picker stick, means on said primary bracket defining three vertically spaced pivot bearings, means on said secondary bracket defining a pair of vertically spaced pivot bearings, a first link pivotally mounted between one of said primary bracket pivot bearings and one of said secondary bracket pivot bearings, a pair of toggle connected links having their free ends respectively pivotally connected to a second pivotal bearing of said primary bracket and a second pivot bearing of said secondary bracket, means on one of said toggle connected links defining a pivot bearing intermediate the ends thereof, and a fourth link pivotally connected between the third pivot bearing of said primary bracket and said intermediate pivot bearing on said one of the toggle connected links, said links being proportioned to control the movements of the picker stick to shift the shuttle contacting portions thereof along a substantially straight line path.

6. A linkage for controlling the movements of a picker stick of a loom, comprising a primary bracket adapted for securement to the rock shaft of the loom, a secondary bracket adapted for securement to a picker stick, means on said primary bracket defining three vertically spaced pivot bearings, means on said secondary bracket defining a pair of vertically spaced pivot bearings, a first link pivotally connected between the uppermost pivot bearing on said secondary bracket and the intermediate pivot bearing of said primary bracket, a pair of toggle connected links having their free ends respectively connected to the lowermost pivot bearing on said secondary bracket and uppermost pivot bearing on said primary bracket, means on the lowermost one of said toggle connected links defining a pivot bearing intermediate the ends thereof, and a fourth

link pivotally connected between the lowermost pivot bearing of said primary bracket and said intermediate pivot bearing on said lowermost toggle connected link, said links being proportioned to control the movements of the picker stick to shift the shuttle contacting portions thereof along a substantially straight line path.

7. A linkage for controlling the movements of a picker stick of a loom, comprising a primary bracket adapted for securement to the rock shaft of the loom, a secondary bracket adapted for securement to a picker stick, means on each of said brackets defining a pair of vertically spaced pivot bearings, a first link pivotally connected between the two lower pivot bearings of said primary and secondary brackets, means on said first link defining a pivot bearing intermediate its ends, a pair of toggle connected links respectively pivotally connected between said intermediate pivot bearing on said first link and the upper pivot bearing on said primary bracket, one of said toggle connected links having a third pivot bearing located thereon, and a fourth link pivotally connected between said third pivot bearing of said toggle connected links and said upper pivot bearing on said secondary bracket, said links being proportioned to control the movements of said picker stick to shift the shuttle contacting portions thereof along a substantially straight line path.

8. A parallel motion picker stick linkage for a shuttle loom comprising, a primary bracket, a picker stick bracket and a plurality of link elements pivotally connecting said brackets, said plurality of link elements including a first generally horizontally disposed link pivotally connected to said picker stick bracket and said primary bracket to resist horizontal forces, a second generally horizontally disposed link pivotally connected to one of said brackets and having a free end providing a pivot bearing, and a toggle joint comprising a pair of generally vertically disposed links arranged to resist vertical forces between the picker stick bracket and the primary bracket and being pivotally jointed together end to end, one of said toggle joint links defining a pivot bearing for connection with the pivot bearing defined by said second generally horizontally disposed link.
